Primary Examiner — Jonathan J Han*Assistant Examiner* — Amanda J Berlinski(74) *Attorney, Agent, or Firm* — Sughrue Mion, PLLC(57) **CLAIM**

The ornamental design for an inhaler, as shown and described.

DESCRIPTION

FIG. 1 is a front perspective view of an inhaler.

FIG. 2 is a rear view of the inhaler of FIG. 1.

FIG. 3 is a front view of the inhaler of FIG. 1.

FIG. 4 is a right side view of the inhaler of FIG. 1.

FIG. 5 is a left side view of the inhaler of FIG. 1.

FIG. 6 is a top view of the inhaler of FIG. 1; and,

FIG. 7 is a bottom view of the inhaler of FIG. 1.

The broken lines shown in the figures depict portions of the inhaler that form no part of the claimed design.

1 Claim, 7 Drawing Sheets(56)
